UNITED STATES PATENT OFFICE.

THOMAS W. CAPEN, OF MILWAUKEE, WISCONSIN, ASSIGNOR TO ALLIS-CHALMERS COMPANY, OF MILWAUKEE, WISCONSIN, A CORPORATION OF NEW JERSEY.

GYRATORY CRUSHER.

1,029,742.

Specification of Letters Patent.

Patented June 18, 1912.

Application filed November 13, 1909. Serial No. 527,767.

To all whom it may concern:

Be it known that I, THOMAS W. CAPEN, a citizen of the United States, residing at Milwaukee, in the county of Milwaukee and 5 State of Wisconsin, have invented certain new and useful Improvements in Gyratory Crushers, of which the following is a specification.

This invention relates to improvements 10 in the construction of crushers of the type in which the crushing head is given a gyratory movement within a stationary shell.

An object of the invention is to provide a crusher which is simple and efficient in construction and operation, and in which the overall height is reduced to a minimum, a feature particularly desirable in portable crushers.

Another object is to produce a crusher in 20 which the hopper opening is entirely free from obstruction such as spider arms.

Still another object is to provide an adjustment of the concave support whereby the size of crushed material may be determined and the support be held rigid at any adjusted position.

A clear conception of the invention can be obtained by referring to the accompanying drawings in which like reference characters 30 designate the same or similar parts in different views.

Figure 1 is a central vertical section through a crusher, built according to the invention. Fig. 2 is a vertical section of 35 the crusher taken on the line II—II of Fig. 1, looking in the direction of the arrows. Fig. 3 is a horizontal section of the device taken on the line III—III of Fig. 1, looking in the direction of the arrow. Fig. 4 is a 40 similar section taken on the line IV—IV of Fig. 1, looking in the direction of the arrows. Fig. 5 is a central vertical sectional view of a modification.

The hopper 1 of the crusher, see Fig. 1, 45 rests upon an upper surface of the concave support 2 and the concaves 9. The concave support 2 is fitted into the crusher frame 11, being held in place for any desired adjustment by the bolts 12 and the jack screws 10.

50 The frame 11 is cylindrical in shape, see Figs. 3, 4, and has a central portion 26 which is connected to the outer wall by the ribs 13, the discharge openings 25 being formed between the ribs 13. The central 55 portion 26 forms the support for the stand-

ard 7 concentric with the frame 11 and clamped to the portion 26 by the nut 16. The drive shaft 5 has a driving gear 19 fastened to its lower end and keyed thereto by means of a key 18, and passes through and 60 finds bearing in a central opening in the standard 7. The eccentric 4 is a cylindrical piece having an eccentric bore and is fastened to the upper end of the shaft 5 and keyed thereto by means of a key 17, and 65 rests upon a wearing plate 6 on top of the standard 7, the eccentric bore fitting and bearing on said standard. The crusher head 8 is centrally mounted on the eccentric 4 and is loose thereon. The head 8 rests 70 upon the wearing ring 14 supported by the frame portion 26. The cap 3 which is attached to the upper portion of the crushing head 8, covers the eccentric 4 and the shaft 5.

The chamber 15 is formed in the frame 11 below the central portion 26 out of direct path of the discharge of material through the openings 25, see Figs. 1, 4. The gear 19 on shaft 5 and pinion 22 meshing therewith are located within the chamber 15. 80 The pinion 22 is keyed to the shaft 21 by a key 23, the shaft 21 being suspended by a bearing 20 which is bolted to the frame 11 underneath one of the ribs 13.

In the modification of Fig. 5, there is no 85 central standard as in the modification of Fig. 1 and the eccentric element actuating the crusher head 8 is formed directly on the shaft 5 as an eccentric portion 32. The shaft 5 finds bearing in the frame 11 at two places, 90 one in the frame portion 34 at the central portion 26, and the other bearing 36 in the frame portion 38 with an interposed wearing step plate 37 under shaft 5. A bushing 33 is interposed between the head 8 and the 95 eccentric portion 32 of the shaft 5 and serves as a convenient means for centering the cap 31 by placing the cap with its counterbore fitting the upper projecting end of the bushing. The remaining structure is similar to 100 that of the modification of Fig. 1.

In the operation of the crusher, the shaft 5 is rotated by means of the gear 19, pinion 22 and shaft 21 from some convenient source of power. This gives a rotary motion to 105 the eccentric 4 or eccentric portion 32, which in turn gives a parallel gyratory motion to the crushing head 8. The material to be crushed is admitted into the freely open annular space between the gyrating head 8 110

and the concaves 9 through the hopper 1. As the material advances toward the bottom of the crusher, it is ground finer until finally it is discharged through the openings 25. 5 The adjustment of the concave support 2 is made by locating jack screws 10 to the desired level, and then screwing down the nuts on bolts 12.

It should be understood that it is not 10 desired to be limited to the exact details of construction shown and described, for obvious modifications will occur to a person skilled in the art.

It is claimed and desired to secure by 15 Letters Patent:-

1. The combination in a crusher, of a shell, a crusher head within said shell, said head having a through bore, a rotatable shaft, a bearing for said shaft supported only from underneath said shell, and a cylindrical eccentric rigid with said shaft and located within said bore in said head, and means for rotating said shaft. 20

2. The combination in a crusher, of a shell, a crusher head within said shell, a rotatable shaft, a bearing for said shaft supported only from underneath said shell, a standard supported from underneath said shell, a single cylindrical eccentric rigid with said shaft and bearing on said standard and located within said head, and means for rotating said shaft. 25

3. The combination in a crusher, of a

shell, a concave support within said shell, concaves within said support, a crusher head 35 within said shell, support and concaves, a rotatable shaft, a bearing supported only from underneath said shell, a means eccentrically rigid with said shaft and located within said head, means for rotating said 40 shaft, and means for vertically adjusting said concaves and support.

4. The combination in a crusher, of a shell, a concave support within said shell, concaves within said support; a crusher head 45 within said shell, support, and concaves; a rotatable shaft, a bearing supported only from underneath said shell, a means eccentrically rigid with said shaft and located within said head, means for rotating said 50 shaft, means for vertically adjusting said concaves and support, and means for holding said concaves and support in adjusted position.

5. In a crusher, concaves, a fixed standard 55 within said concaves, a rotatable cylindrical eccentric bearing on said standard, a crusher head having a through bore within which said eccentric is located, and a shaft in said standard for rotating said eccentric. 60

In testimony whereof, I affix my signature in the presence of two witnesses.

THOMAS W. CAPEN.
